Albert Granger

Design for Metal Pen

Patented April 15, 1856.

A drawing representing (in due like size) the Washington Metal Pen
for the design of which, I have made an application for issued patent,
and filed my specification with reference to this drawing.
Signed & Mailed, 31st 1856.

Albert Granger

Albert Granger of New York, N. Y.
Letters Patent No. 780. Dated April 15th 1856.

The Schedule referred to in these Letters Patent, and
making part of the same.

To all whom it may concern:

Be it known that I, Albert Granger
of the City, County and State of New York, have invented
a new design for a Steel Pen; And I do hereby declare
that the following is a full and exact description of
said design.

The new feature as compared with any other steel
pen now manufactured, is the impression (on that part
known to pen manufacturers as the "heel" of the pen, as shown
at letter A, in the accompanying drawing) of a medallion
bearing a likeness of Washington, in basso relief F.

Hence the appellation - "Washington Medallion Pen".
The middle third part of the pen (B) is in form depressed,
from the top of the hole in the "nib" (C) to the base of the
"Washington Medallion". This depression is divided in
the centre by a ridge (D) raised gradually from either side.

The sides of the depressed middle of the pen (B) are
cut out in a concave form (E).

What I claim as my invention, and desire
to secure by letters patent, is the device impressed on the pen,
namely, a medallion bearing a likeness of Washington.
